UNITED STATES PATENT OFFICE.

GEORGE HASECOSTER, OF ST. LOUIS, MISSOURI.

FURNACE FOR STEAM-BOILERS.

SPECIFICATION forming part of Letters Patent No. 350,245, dated October 5, 1886.

Application filed March 25, 1886. Serial No. 196,538. (No mo'l el.)

To all whom it may concern:

Be it known that I, GEORGE HASECOSTER, of the city of St. Louis, and State of Missouri, have invented a new and Improved Furnace 5 for Steam-Boilers, of which the following is a full, clear, and exact description.

The object of my invention is to provide a new and improved furnace for steam-boilers and for other purposes, in which a complete 10 combustion of the fuel is accomplished by introducing a mixture of steam, hot air, and gases into the fuel.

The invention consists in a specially-constructed furnace and chimney, and in an apparatus 15 for forcing a mixture of hot air, steam, and gases into the fuel.

The invention also consists of various parts and details, as will be fully described herein-after, and then pointed out in the claims.

Reference is to be had to the accompanying 20 drawings, forming a part of this specification, in which similar letters of reference indicate corresponding parts in all the figures.

Figure 1 is a longitudinal sectional elevation 25 of my improvement. Fig. 2 is a sectional plan view of the same on the line *x x*, Fig. 1. Fig. 3 is a cross sectional elevation of the same on the line *y y*, Fig. 2. Fig. 4 is a sectional elevation of the chimney on the line *z z*, Fig. 2. Fig. 5 is a cross-section on the line *u u*, Fig. 1. The steam-boiler *A*, of any approved construction, is mounted in the furnace *B*, provided with the usual grate-bars, *C*, the ash-pit *D*, the doors *D'*, leading to the ash-pit, and the 30 doors *E'*, opening into the combustion-chamber *E* above the grate-bars.

The bridge-wall *F* at the inner end of the grate-bars *C* is provided with a partition-wall, *G*, which divides the furnace into two main 40 compartments—the combustion-chamber *E* and the hot-air chamber *H*. The bridge-wall *F* is provided with several flues, *F'*, which commence under the grate-bars *C*, run inward and then upward, and open into the combustion-chamber *E* at the rear of the grate-bars *C*.

In the side walls, *B'*, of the furnace *B* are ducts or flues *I'*, which lead from the ash-pit *D* to the vertical passage *I'*, which connects at its top by the flue *I* with the combustion-chamber *E*. The flue *I'* is provided with a damper, *I''*, which can be opened or closed from the front of the furnace by a damper-rod, *I'''*.

Into the bottom of the ash-pit *D* opens a flue or duct, *J*, which connects with the mixing apparatus *K*, placed on the outside of the 55 side wall, *E'*, and connecting with the hot-air chamber *H* and a chimney, *M*, by the transverse channel *N*. The latter is arched at two or more places, so as to reduce the opening *N'*, leading from the hot-air chamber *H* into the 60 channel *N*. The hot-air chamber *H* is provided with a bottom, *H'*, which is curved upward from the rear end toward the channel *N*, and is also provided with a door, *H''*, through which ashes and cinders which accumulate in 65 the hot-air chamber *H* can be removed.

The mixing apparatus *K* consists of a fan, *K'*, which is rotated in any convenient manner, into which apparatus opens a pipe, *K''*, admitting steam, and it is also provided with 70 an opening, *K'''*, through which air can pass into the fan from outside. The heating of the journal-box *O* of the mixing apparatus *K* is prevented by the circulation of cold water around the fan-shaft *O'* in the journal-box *O*, 75 said water being supplied by a small pipe, *O''*, and drawn off through the pipe *O'''*. The channel *N* is provided at its entrance to the chimney *M* with a hinged damper, *P*, operated from the front of the furnace by the damper-rod *P'*. The chimney *M* is provided on its 80 three outer sides with doors *Q*, *Q'*, and *Q''*, of which the door *Q* leads directly into the central chimney-opening, *M'*, while the doors *Q'* and *Q''* connect with the vertical side flues, *R*, 85 which open into the central opening, *M'*, by means of the apertures *R'*. The opening of the flue *J* into the ash-pit *D* can be closed by the door *S*, so as to prevent ashes and cinders from falling into the said flue when being removed from the ash-pit.

The operation is as follows: The flames and heated gases from the fire on the grate-bars *C* rise and lap up on the sides of the boiler and on the front end of the same in the combustion-chamber *E*. The heated gases and flames enter the boiler flues *A'* at the front end of the boiler *A*, and, passing through the same, enter the hot-air chamber *H*, from which they are drawn up the inclined bottom *H'* into the channel *N* by the suction of the fan *K'* and the draft of the chimney *M*. That portion of the unconsumed products of combustion which passes into the chimney is drawn thereinto by the

draft or circulation set up by the action of the fan, the same consisting in the current of air forced from the fan through the pipe J into the chamber D, through the passages I² I' I into the chamber E, thence through the boiler-tubes and into the hot-air chamber H, whence the same will be forced through the opening N' into the channel N above the damper P and into the central opening or passage, M', of the chimney, passing thence into the open air. The remainder of the heated products, consisting of combustible gases and hot air, passes into the mixing apparatus K, where it is mixed by the action of the fan K' with the steam (generally exhaust-steam) entering through the pipe K² and with the fresh air entering from the chimney M. This mixture is then diverted into the flue J and enters the ash-pit D, from which part of it passes directly through the grate C into the burning fuel, part enters the flues F' and passes from the rear into the combustion-chamber E and over the fuel on the grate-bars C, and part of the mixture passes into the side passages, I', and up through the same, and enters the combustion-chamber E by means of the openings I. The amount of the mixture which enters the side passage, I', can be regulated by the damper I'. The heated products, gases, &c., pass then from the combustion-chamber into the flues A' of the boiler A, as before described. Air from the outside can enter the chimney M by the side doors Q' and Q², and, after passing up the side flues, R, enters the central opening, M', of the chimney, is forced downward in the same by the suction of the fan K', and is heated in this downward motion by the incombustible and unconsumed gases passing up the central shaft, M', as before described. The outside air is drawn into the chimney by reason of the suction of the fan, the same as before stated, taking or drawing into the mixer a portion of the products of combustion and forcing or sending it into the chimney, as above described, thus creating a partial vacuum in the chimney, assisting the downward passage or entrance of the air from the side ducts, R, of the chimney into the central opening, M', thereof, while the inlet to the channel N from the chimney is of greater area than the inlet thereto from the hot-air chamber H, whereby the cold or fresh air currents, which are heavier than the warm-air currents, will descend, passing closely along the sides of the chimney and the bottom of the channel N, under the valve P, whence it passes into the suction side of the mixer, thus effecting the aforesaid result. The complete combustion of the fuel is thus attained by my improved furnace, the combustible gases being forced from the hot-air chamber into the combustion-chamber, and being additionally charged with a mixture of steam and air.

Having thus fully described my invention, I claim as new and desire to secure by Letters Patent—

1. In a furnace, the combination of a boiler, a combustion-chamber, and a partition-wall, with a hot-air chamber, a channel, a mixing apparatus, and a return-flue, substantially as herein shown and described. 70

2. In a furnace, the combination of a boiler, a combustion-chamber, an ash-pit, and a partition-wall, with a hot-air chamber, a channel, a mixing apparatus, and a return-flue, substantially as herein shown and described. 75

3. In a furnace, the combination of a boiler, a combustion-chamber, an ash-pit, and a partition-wall, with a hot-air chamber, a channel, a chimney, a mixing apparatus, and a return-flue, substantially as herein shown and described. 80

4. In a furnace, the combination of a boiler, a combustion-chamber, an ash-pit, a bridge-wall, and a partition-wall, with a hot-air chamber, a channel, a chimney, a mixing apparatus, and a return-flue, substantially as herein shown and described. 85

5. In a furnace, the combination of a boiler, a combustion chamber, an ash-pit, a bridge-wall provided with flues, a partition-wall dividing the furnace into two main compartments, and side passages which connect the ash-pit and the combustion-chamber, with a hot-air chamber, a channel, a chimney, a mixing apparatus, and a return-flue, substantially as herein shown and described. 95

6. In a furnace, the combination of a boiler, a combustion-chamber, an ash-pit, and grate-bars, with the bridge-wall provided with flues which connect the ash-pit with the combustion-chamber from the rear, and a partition-wall, substantially as herein shown and described. 100

7. In a furnace, the combination of a boiler, combustion-chamber, an ash-pit, and grate-bars, with side passages leading from the ash-pit to the combustion-chamber, a bridge-wall having flues leading from the ash-pit to the combustion-chamber, and a partition-wall, substantially as herein shown and described. 105

8. In a furnace, the combination of a hot-air chamber with a channel and a mixing apparatus provided with a fan, a steam-inlet, and a cold-air inlet, and connected with a return-flue entering the ash-pit, substantially as herein shown and described. 110

9. In a furnace, the combination of a hot-air chamber, a transverse channel, and a mixing apparatus, with a chimney having a central shaft, side passages, and air-inlet doors, substantially as herein shown and described. 115

10. In a furnace, the combination of a hot-air chamber, a transverse channel provided with a damper, and a mixing apparatus, with a chimney having a central shaft, side passages, and air-inlet doors, substantially as herein shown and described. 120
